VEGETABLE SLICING MACHINE

Joseph A. Miller, Rochester, N. Y., assignor to
 Boutell Manufacturing Company, Rochester,
 N. Y., a corporation of New York

Application January 25, 1940, Serial No. 315,609

8 Claims. (Cl. 146—169)

The present invention relates generally to vegetable slicing machines and more particularly to a power-operated machine for slicing pickles, that is, sweet mixed, or chunked pickles and 5 bread-and-butter or sandwich pickles or chips, and having as a requisite for this purpose changeable slicing blades and plungers, or more especially knife heads and plunger heads.

The invention further relates to machines of 10 the type in which the pickles are fed to the slicing mechanism by mechanical means from a feed station upon which they are placed by hand, and, in view of the close proximity of the feed station to the slicing mechanism, and from the 15 standpoint of safety of the operator, it is an object of the invention to provide a feed arrangement of a nature to insure effective mechanical alignment of the pickles by the mechanical feed means after they have been placed manually at 20 the feed station without regard to alignment.

In connection with the slicing of certain pickles, more especially what are known as sweet mixed pickles, it is a well-known fact that it is desirable to cut the same longitudinally as well 25 as transversely so as to halve the round slices, and it is an important requisite of this invention to provide for the ready effective installation and use, when it is desirable and necessary, of a longitudinal splitting knife in cooperative arrangement with the slicing blades for the lengthwise 30 splitting of the pickles as they are sliced.

Other objects of the invention as well as the resulting advantages thereof, residing more particularly in its various details, will clearly appear 35 in the course of the following description, in which reference is made to the accompanying drawings forming a part of this specification, and wherein:

Figure 1 is a perspective view of the complete 40 machine;

Figure 2 is a side view thereof;

Figure 3 is a front view;

Figure 4 is a detail fragmentary sectional view 45 through one of the walls of the knife box, showing the longitudinal splitting knife in position, and taken substantially on the line 4—4 of Figure 5;

Figure 5 is a similar view taken substantially on the line 5—5 of Figure 4;

Figure 6 is an enlarged vertical transverse sectional view taken substantially on the line 6—6 of Figure 3;

Figure 7 is a horizontal sectional view taken 50 substantially on the line 7—7 of Figure 3, showing the knife box in top plan view;

Figure 8 is a detail perspective view of one of the plunger blades together with certain of the connections thereof; and

Figure 9 is a detail perspective view of one of the slicing knives.

Referring now to these figures and more particularly to Figures 1, 2, 3 and 6, there is shown a slicing machine, the principal support of the parts of which is derived from the secure connection of the knife box, generally indicated at 10 10, to a support, which may be a slicing table or the frame of a conveyor, by which conveyor the sliced pickles are continuously displaced from beneath the knife box for inspection purposes, particularly where it is desired to move the ends 15 and badly misshapen pieces.

By comparison of Figures 3 and 6, it will be noted that the front and rear walls 11 and 12 of the knife box are inclined in an upward direction toward one another, while the side walls 13 are 20 upright. These walls are integral with one another at the corners of the box, which, it will be noted, is generally of oblong shape, and are similarly united at their lower edges to a horizontally outstanding and surrounding flange 14, the latter of which is widest beyond the sides 12 of the box for the reception of bolts or other fastening members 15, by means of which the knife box as a whole may be rigidly connected to supports of the nature above set forth, and to further 25 provide for rigid and preferably integral upright anchoring sockets 16 disposed wholly beyond the side walls 12.

Securely and rigidly bolted or otherwise anchored at their lower ends in the anchoring 35 sockets 16 are a pair of cylindrical uprights or frame bars 17 rising in line with the horizontal longitudinal axis of the knife box. To the upper ends of the frame bars 17 are similarly bolted or otherwise rigidly secured the end sockets 18 of 40 a platform 19 for the support of a gear box 20, through which a driven shaft 21 is mounted. Gears within the gear box 20 connect the driven shaft 21 with the shaft of a motor 22, if such motor is used for the power operation of the machine, the rear end of the shaft 21 being preferably provided with a pulley 23, whereby the machine may be connected by a belt 24 to a source of distant power, it being noted that the motor 22, if used, is mounted directly on the platform 19 as plainly shown in Figures 1 and 3.

At the forward end of the driven shaft 21 is a crank disk 25, from which a crank arm 26 depends, the lower end of this crank arm being pivotally connected at 27 to a crosshead made up 50

of a cross bracket 28 having vertically tubular bearing members 29 integral with its opposite ends and slidably disposed upon the upright frame bar 17 for guided movement under actuation 5 of the power connections just described within the space between the top of the knife box 10 and the platform 19. One of these tubular bearings 29 of the crosshead, it will be noted, is provided with a laterally projecting stud 30 for 10 the movable connection of the upper end of a side connecting rod 31, for a purpose which will presently appear.

Where the knife box 10 is securely fastened, as by bolting, to a table, the open base of the knife 15 box is positioned above an opening in the table so that the sliced pickles may fall into a suitable receptacle, and this is generally indicated in Figure 6, where the table or other support is indicated at A with an opening A' inverted in alignment 20 with the open base of the knife box.

The knife assembly or head consists of a series 25 of V-shaped slicing blades or knives 32, one of which is shown in detail in Figure 9, and a pair of supporting rods 33, the latter of which extend through openings in the side walls 12 of the knife box, these rods traversing the knife box within its upper front and rear portions, parallel to the front and rear walls 11 and 12. As will be noted from Figure 9, each slicing knife or blade 32 has 30 openings 34 through the free ends of its diverging portions, each of which diverging portions has a cutting edge 35. The rods 33 extend through the openings 34 and also through spacing rings 36 between the knives or blades 32, and it is these 35 rods, spacing rings 36, and series of knives or blades spaced and clamped thereby which constitute the slicing or cutting head, disposed, as above stated and as plainly seen in Figure 6, wholly within the knife box 10, so that the several knives or blades cooperate in their V-shape 40 formation to constitute therein a longitudinal pickle receiving trough.

At the front of the knife box there is bolted or otherwise securely fastened thereto a forwardly 45 and downwardly curved pickle feed plate 37, the upper rear edge of which terminates flush with the upper edge of the front wall 11 of the knife box, along the full length of which the feed plate 37 extends. This feed plate curves forwardly 50 and downwardly to a point substantially forwardly of the front wall 11 of the knife box as well as to a point at least midway of the height of the knife box, so as to provide for a pickle receiving station, where the pickle is initially placed by 55 hand, by the operator, at a point substantially remote from the upper open end of the feed box.

Mounted to sweep along the upper surface of the curved feed plate 37 from the lower forward edge thereof to its upper rear edge is a longitudinally disposed, angularly shaped feed bar 38 formed in connection at its opposite ends with a pair of angular side arms 39, the latter of which are pivotally mounted at 40 at their rear ends upon bolts or studs secured to the lower forward 60 portions of the side walls 12 of the knife box, one of these side arms 39 being in connection, through the connecting rod 31 previously mentioned, with the crosshead 28, so that, as the crosshead slides upwardly, the lever 42 will be 65 swung upwardly and rearwardly, and consequently the feed bar 38 will be shifted upwardly along the feed plate 37, whereby a pickle placed manually on the feed plate 37 by the operator with the parts in the position shown in Figure 6, will 70 be shifted upwardly along the feed plate and 75

finally discharged into the feed box, where it will come to rest in the trough formed by the V-shaped knives of the knife or cutting head. It will be noted in this respect that the feed plate 37 is curved on the arc of a circle having its center at the pivots 40 of the side arms 39 of the feed bar 38 and that the arrangement permits of the manual disposal of a pickle in connection with the feed means at a point remote from the upper open end of the knife box 10, so that it is entirely unnecessary for the hands of the operator to dangerous approach those portions of the machine including the knives or blades 32, involved in the pickle cutting operation. It is to be further noted at this point that the arrangement 15 also provides for sliding movement of the pickle over substantially the entire surface of the feed plate 37, which gives rise to the further advantage that it eliminates the necessity for great care in the manual placement of the pickles on the feed 20 plate. Ordinarily the pickles are laid on the feed bar 38 and parallel therewith, but, if for any reason in the hurried moments of continuous operation, a pickle is carelessly placed on end, that is, more or less at right angles to the feed bar 25 38, it will be straightened out in alignment along the feed bar as the latter moves upwardly across the feed plate 37, since, during this movement, the pickle slides on the feed plate and has sufficient frictional contact therewith to bring about 30 alignment or proper lengthwise positional relationship of each pickle before it is discharged into the feed box.

For the safe operation of the feed bar by the up and down movements of the crosshead 28, 35 there is rigidly connected to one of the side arms 39, as best seen in Figures 3 and 6, an angular bracket 41 which outstands laterally of said arm and pivotally supports a socketed connecting member or head 42. Securely fastened in the 40 socket of the connecting member or head 42 as by means of a set screw 42^a is the lower end of the before-mentioned connecting rod 31, whose upper end joins the stud or projecting member 30 of the crosshead in a manner promoting a definite factor 45 of safety in operation as will be now described.

The upper end of the connecting rod 31 passes loosely through a somewhat larger opening in the projecting member 30 and also through compression springs 31^a and 31^b, whose adjacent ends 50 bear against opposite sides of said projection. These springs are compressed between the projection 30 and collars 43 secured on the connecting rod 31, and are of sufficient strength to normally transmit the reciprocating movement of 55 the crosshead 28 to the swinging feed member. In this connection it will be noted that but little power is needed in the normal feed of pickles upwardly along the feed plate 37 and that the springs 31^a and 31^b make it possible for the operator to hold the feed bar relatively stationary during continued operation of the crosshead in any instance where a portion of the operator's hand or clothes become caught in the feed member. 65

To cooperate with the cutting or slicing head, a plunger head is utilized in connection with the crosshead 28, this plunger head consisting of a T-shaped bar 44, whose upstanding rib seats against the lower surface of the crosshead 28 70 between the slide members 29 and whose opposite ends are provided with flanges 45, as best seen in Figures 1 and 3, for secure connection by bolts and the like to the crosshead, it being noted that this rib is recessed at spaced points at 46 75

to provide for the reception of bolts 47 and nuts engaging the upper ends of these bolts, as utilized in the connection of the plunger disk assembly to be now described.

5 The plunger disk assembly includes a series of plunger disks 48, of which a single disk is shown in detail in Figure 8. These disks, which are used singly or in pairs, separated by spacing rings 49, present lower flat edges 50 and have 10 openings 51 in their upwardly tapering portions to receive therethrough a clamping rod 52, which also extends through the spacing rings 49 and receives at its threaded ends bolts and clamping rings 53, whereby the several plunger disks are 15 thus rigidly clamped in spaced relation by means disposed adjacent to their upper ends, so that the lower ends are free to pass downwardly through the spaces between the slicing blades 32. The use of the plunger disks 40, either singly or 20 in pairs, depends upon the desired thickness of the pickles slices and thus upon the spacing of the blades 32 in the knife head. The aforementioned bolts 47, which connect the plunger disk assembly with the T-shaped bar 44 of the plunger 25 head, have their lower ends threaded into certain of the spacing rings 49 as shown in Figure 8.

Thus with the plunger head properly secured in position and the disks thereof spaced to accord with the desired spacing of the knife blades 32 in the knife head, each downward movement 30 of the crosshead 28, from the position shown in Figure 3 to the position shown in Figure 6, shifts the several plunger disks 48 downwardly through the spaces between the slicing blades 32, and it 35 is to be noted from Figure 6 that it is preferable this movement be such as to carry the lower straight edges 50 of the plunger blades 48 to a lowermost point coincident with the lowermost points of the blades 32 or slightly above such lowermost points of the blades, for a purpose to 40 now appear.

It will be noted from Figures 1, 2 and 6 that the lower portions of the side walls 13 of the knife box 10 are recessed or cut away above the 45 surrounding flange 14 of the knife box, so that they present substantial free lower edges above and inwardly beyond the end portions of the knife box flange 14. These lower edges of the 50 end walls 13 are provided with vertical slots 53 to receive the end portions of a longitudinal splitting knife 54 whose upper cutting edge 55 may be presented snugly against the lowermost central points of the several slicing blades 32. The lower portions of the end walls 13 at the 55 lower ends of the slots 53 are also tapped to receive threadedly adjustable clamping screws 56, as best seen in Figures 4 and 5, which engage the lower edges of the splitting knife 54 at its 60 opposite ends to hold the splitting knife firmly positioned against and along the knife head.

Thus when the plunger descends, each pickle will be forced down through the slicing blades 32 and each pickle so sliced will be also forced 65 downwardly against the splitting blade 54, so that it will be split lengthwise and the slices thus cut in half, as indicated in Figure 6.

It is obvious that the splitting knife 54 may be 70 used whenever desired and that it may be readily installed when its use is desired and removed at other times without disturbing the knife head, and, where the machine as a whole is used above a table opening as previously described, it is possible to install and remove the splitting knife 75 from beneath the table without detaching the

machine from the table, as might otherwise be necessary.

It is to be understood from the foregoing that it is contemplated the cutting blades as well as the disks in the plunger head may be formed 5 of thin material, of non-oxidizing nature, such as stainless steel, which is not affected by the acids of the pickles or such other vegetables as may be sliced, and which is capable of being readily maintained in a cleanly, sanitary con- 10 dition.

What is claimed is:

1. A slicing machine comprising a knife box open at the top and bottom thereof and having means for securing the same upon a stationary 15 support, a knife head therein including a series of V-shaped slicing knives having inner cutting edges, and means rigidly connecting and clamping the upper outer ends of said knives in spaced apart relation to form an upwardly opening 20 trough in the head for the reception of the vegetables to be sliced, and a plunger having guided movement vertically into and out of the knife box and including a head comprising a series of plunger disks for passage downwardly between 25 the cutting knives of the knife head, said plunger disks presenting lower horizontal straight edges, and means extending through the upper portions of the series of plunger disks and rigidly connecting the same in spaced apart relation coin- 30 ciding with the spacing of the slicing knives.

2. A slicing machine comprising a knife box open at its top and bottom and having means for securing the same upon a stationary support, a knife head therein including a series of V- 35 shaped slicing knives having inner cutting edges, and means for rigidly clamping the same in spaced apart relation to form an upwardly opening trough for the vegetables to be sliced, a plunger having guided movement vertically into 40 and out of the knife box and including a series of spaced apart rigidly clamped plunger disks for passage between the slicing knives, and a longitudinal splitting knife detachably positioned in connection with portions of the knife box and 45 presenting an upper cutting edge centrally along and beneath the slicing knives of the knife head.

3. A slicing machine comprising a knife box open at its top and bottom and having means for securing the same upon a stationary support, 50 a knife head therein including a series of V-shaped slicing knives having inner cutting edges, and means for rigidly clamping the same in spaced apart relation to form an upwardly opening trough for the vegetables to be sliced, a plunger having guided movement vertically into 55 and out of the knife box and including a series of spaced apart rigidly clamped plunger disks for passage between the slicing knives, a longitudinal splitting knife detachably positioned in 60 connection with portions of the knife box and presenting an upper cutting edge centrally along and beneath the slicing knives of the knife head, and means in connection with the side walls of the knife box for supporting said splitting knife 65 and adjustably maintaining its said cutting edge against the lower edges of the slicing knives.

4. A slicing machine comprising a knife box open at its top and bottom and having means for securing the same upon a stationary support, a 70 knife head therein including a series of V-shaped slicing knives having inner cutting edges, and means for rigidly clamping the same in spaced apart relation to form an upwardly opening trough for the vegetables to be sliced, a plunger 75

having guided movement vertically into and out of the knife box and including a series of spaced apart rigidly clamped plunger disks for passage between the slicing knives, a longitudinal splitting knife detachably positioned in connection with portions of the knife box and presenting an upper cutting edge centrally along and beneath the slicing knives of the knife head, the side walls of the knife box having vertically disposed slotted 5 openings in which the end portions of the splitting knife are adjustably seated, and clamping means cooperating with said side walls of the box and engaging the splitting knife for firmly holding the latter in position upwardly against 10 the lower ends of the slicing knives.

5. A slicing machine comprising a knife box open at its top and bottom and having means for securing the same upon a stationary support, a longitudinal series of V-shaped slicing 20 knives having inner cutting edges and secured at the upper portions and at laterally spaced points within the knife box to present a vegetable receiving trough, a plunger having guided movement vertically into and out of the knife box and 25 including rigidly clamped plunger disks spaced apart in accordance with the spacing of the slicing knives for passage downwardly between the latter, and feed means for supplying vegetables to the upper end of the knife box and to the 30 trough formed by the cutting knives, consisting of a forwardly and downwardly curved feed plate attached to the forward wall of the box and outstanding therefrom to a point safely remote from the plunger and slicing knives, and plunger actuated means movable along the feed plate from 35 its front to its rear for shifting manually disposed vegetables in sliding contact with the feed plate from the lower front portion thereof into the knife box.

40 6. A slicing machine comprising a knife box open at its top and bottom and having means for securing the same upon a stationary support, a longitudinal series of V-shaped slicing knives having inner cutting edges and secured at the 45 upper portions and at laterally spaced points within the knife box to present a vegetable receiving trough, a plunger having guided movement vertically into and out of the knife box and including rigidly clamped plunger disks 50 spaced apart in accordance with the spacing of the slicing knives for passage downwardly between the latter, and feed means for supplying vegetables to the upper end of the knife box and to the trough formed by the cutting knives, consisting of a forwardly and downwardly curved feed plate attached to the forward wall of the box and outstanding therefrom to a point safely remote from the plunger and slicing knives, plunger actuated means movable along the feed 55 plate from its front to its rear for shifting manually disposed vegetables in sliding contact with the feed plate from the lower front portion thereof into the knife box, said means including a feed bar disposed longitudinally of the feed plate, having side arms pivotally connected to the knife box, and a connecting rod pivotally connected to the plunger and to one of said side arms for

actuating the feed bar in timed relation to the movements of the plunger.

7. A slicing machine comprising a knife box open at its top and bottom and having means for securing the same upon a stationary support, 5 a longitudinal series of V-shaped slicing knives having inner cutting edges and secured at the upper portions and at laterally spaced points within the knife box to present a vegetable receiving trough, a plunger having guided movement vertically into and out of the knife box and including rigidly clamped plunger disks spaced apart in accordance with the spacing of the slicing knives for passage downwardly between the latter, and feed means for supplying vegetables to the upper end of the knife box and to the trough formed by the cutting knives, consisting of a forwardly and downwardly curved feed plate attached to the forward wall of the box and outstanding therefrom to a point safely remote from the plunger and slicing knives, plunger actuated means movable along the feed plate from its front to its rear for shifting manually disposed vegetables in sliding contact with the feed plate from the lower front portion thereof into the knife box, said means including a feed bar disposed longitudinally of the feed plate, having side arms pivotally connected to the knife box, a connecting rod pivotally connected to one of the side arms, and spring means between the connecting rod and the plunger through which movements of the plunger are normally communicated to the feed member, said spring means permitting the feed member to be held relatively stationary during continued movement of the 35 plunger.

8. A slicing machine comprising a knife box open at its top and bottom and having means for securing the same upon a stationary support, a longitudinal series of transversely disposed 40 knives supported within said box in spaced apart relation, a plunger having guided movement vertically into and out of the knife box and including a plunger head having a series of plunger disks for movement downwardly between the 45 knives of the knife box, a forwardly and downwardly curved feed plate attached to the front wall of the box and outstanding therefrom to a point safely remote from the plunger and slicing knives, a feed member mounted in connection 50 with the knife box to swing along the face of the feed plate for shifting vegetables in sliding contact with the feed plate and into the knife box, a connecting rod pivotally connected at one end to said feed member, an apertured 55 extension carried by the plunger through which the other end of the connecting rod loosely extends, compression springs around those portions of the connecting rod upon opposite sides of said projection and abutting at one end the opposite 60 sides of the projection, and anchoring members carried by the connecting rod against which the opposite ends of the springs have bearing, whereby to normally actuate the feed member by the movements of the plunger and permit the feed member to be held relatively stationary during 65 continued movements of the plunger.

JOSEPH A. MILLER.
